US0D1096950S

(12) **United States Design Patent** (10) **Patent No.:** **US D1,096,950 S**
(45) **Date of Patent:** **** Oct. 7, 2025**

(54) **HANDHELD CONTROLLER FOR A FLIGHT SIMULATOR OR A REMOTELY CONTROLLED AIRCRAFT**

(71) Applicant: **Yawman LLC**, Carmel, IN (US)

(72) Inventor: **Thomas Michael Nield**, Frisco, TX (US)

(73) Assignee: **Yawman LLC**, Carmel, IN (US)

(**) Term: **15 Years**

(21) Appl. No.: **29/877,029**

(22) Filed: **May 31, 2023**

Related U.S. Application Data

(63) Continuation of application No. 29/800,809, filed on Jul. 23, 2021, now Pat. No. Des. 992,645.

(57) **CLAIM**

The ornamental design for a handheld controller for a flight simulator or a remotely controlled aircraft, as shown and described.

DESCRIPTION

FIG. 1 is a top right rear perspective view of the handheld controller for a flight simulator or a remotely controlled aircraft;

FIG. 2 is a top right front perspective view thereof;

FIG. 3 is a top view thereof;

FIG. 4 is a bottom view thereof;

FIG. 5 is a right view thereof;

FIG. 6 is a left view thereof;

FIG. 7 is a front view thereof; and,

FIG. 8 is a rear view thereof.

The broken lines depict portions of the handheld controller for a flight simulator or a remotely controlled aircraft that form no part of the claimed design.

1 Claim, 7 Drawing Sheets
